UNITED STATES PATENT OFFICE.

ALONZO L. DUNAVAN, OF IZEE, OREGON.

MACHINE FOR GRUBBING SAGE-BRUSH.

No. 802,630.

Specification of Letters Patent.

Patented Oct. 24, 1905.

Application filed February 21, 1905. Serial No. 246,760.

To all whom it may concern:

Be it known that I, ALONZO L. DUNAVAN, a citizen of the United States, residing at Izee, in the county of Grant and State of Oregon, 5 have invented a new and useful Machine for Grubbing Sage-Brush, &c., of which the following is a specification.

This invention relates to machines for grubbing sage-brush and other obnoxious weeds 10 and plants of a like nature; and it has for its object to provide a device of this class which shall possess superior advantages in point of simplicity, durability, and general efficiency.

With these and other ends in view, which 15 will readily appear as the nature of the invention is better understood, the same consists in the improved construction and novel arrangement and combination of parts, which will be hereinafter fully described, and particularly 20 pointed out in the claims.

In the accompanying drawings has been illustrated a simple and preferred form of embodiment of the invention, it being, however, understood that no limitation is necessarily 25 made to the precise structural details therein exhibited, but that the right is reserved to any changes, alterations, and modifications to 30 which recourse may be had within the scope of the invention and without departing from the spirit or sacrificing the efficiency of the same.

In said drawings, Figure 1 is a top plan view of a grubbing-machine constructed in accordance with the principles of the invention. 35 Fig. 2 is a side elevation of the same, the near wheel having been removed. Fig. 3 is a vertical sectional view taken on the line 3 3 in Fig. 1. Fig. 4 is an enlarged perspective, 40 partly in section, showing a portion of the grubbing-roller and related parts. Fig. 5 is an enlarged sectional view of the grubbing-roller.

Corresponding parts in the several figures are indicated throughout by similar characters of reference.

A rectangular frame, comprising the side pieces 1 1, front piece 2, and rear piece 3, supports the side members 4 4 of a tongue 5, said side members converging forwardly in the 50 usual manner. Suitably attached to the under sides of the frame-pieces 1 1 and side members 4 4 are axle-stubs 6, carrying the transporting-wheels 7. In rear of these axle-stubs and partially braced thereby are brackets 8 8, 55 which depend from and are connected with the side members 1 1 of the frame and which

are sustained by auxiliary braces 9, connecting the front and rear sides of said brackets with the under sides of the side frame-pieces 1.

The brackets 8 carry upon their lower front 60 ends boxes or bearings 10 for a cylinder-shaft 11, said boxes or bearings being secured in part by means of the bolts 12, which secure the lower ends of the braces 9 to the brackets 8, and partly by means of hook-bolts 13, which 65 serve for the attachment of the draft.

Mounted eccentrically upon the shaft 11 is a cylindrical member 14, which is termed the "grubbing-cylinder." Said cylinder is provided with transverse sockets, as 15, of approximately triangular shape, for the reception of the inner ends of teeth, as 16, which said teeth are of approximately rhomboidal shape, terminating at their front ends in sharp points 17 and at their rear ends in screw-threaded 75 shanks 18, which protrude upon the back of the roller for the reception of nuts 19, whereby the said teeth will be secured firmly in position.

The grubbing-cylinder is provided with a 80 plurality of earth-engaging pins 18^a, having screw-threaded inner ends and provided with squared outer ends 19^a, adapted to be engaged by a suitably-constructed wrench, whereby the said pins may be screwed into the body 85 of the roller. These earth-engaging pins are to be secured at suitable distances apart around the circumference of the cylinder, and their inner ends are disposed in engagement with opposite sides of the rubbing-teeth, thus assisting 90 in securing the latter and also preventing inward displacement of the said pins.

The ends of the eccentrically-mounted cylinder are provided with collars 21, having radially-extending lugs 22, said lugs at the two 95 ends of the roller being in alignment with each other and adapted to be engaged by latches 23, which are pivotally secured to the inner sides of the brackets 8. These latches, 100 which are in the form of elongated levers provided with engaging members at their front ends, are connected, by means of links 24, with arms 25, extending from a rock-shaft 26, which is suitably supported in the frame of the machine and which is provided with a foot-piece 105 or treadle 27, adapted to be manipulated by the operator, whose seat 30 is mounted upon a platform 29, disposed between the diverging rear ends of the tongue-bars, as best seen in Fig. 1.

The operation of this device will be readily understood from the foregoing description,

taken in connection with the drawings hereto annexed. When the lugs 22 are in engagement with the latches 23, the teeth of the cylinder will point downwardly and forwardly, 5 so as to engage the ground, and when the machine is hauled over the ground the teeth of said cylinder will dig into the soil and uproot the vegetation with which they come into contact. The uprooted plants or weeds will 10 be dragged along with the machine until a sufficient quantity has been accumulated, when, by operating the foot-lever, the driver will release the cylinder and permit the latter to revolve upon the axis of the shaft 11, thus 15 causing the teeth to be disentangled from the brush and weeds engaged thereby, and the several earth-engaging pins upon the roller will, by engaging the surface of the soil, force the cylinder to rotate and to become disengaged from the brush and weeds, which are 20 left behind. The driver in the meantime has restored to their normal position the latches 23, which will presently be engaged by the lugs 22, thereby stopping further rotation of the cylinder and causing the teeth 25 to again engage the earth for a repetition of the operation.

The cylinder has been shown mounted eccentrically; but this is not essential, and it 30 may be concentric with its supporting-shaft, if preferred.

By placing the hooks for the attachment of the draft upon the boxes in which the cylinder-carrying shaft is journaled it is obvious 35 that the draft is directly applied to the ends of the cylinder, thereby achieving much better results than if the draft were attached at any other point of the machine.

To prevent the cylinder, which is intended 40 to be made of wood, from splitting or becoming otherwise damaged, the said cylinder is reinforced by means of longitudinal strips or bars 34 34 and 35, the latter of which is slotted for the passage of the teeth 16, which are 45 thereby very materially braced. I have also in order to increase the strength and effectiveness of the device provided the latch members 23 with heads, as 36, which are of a width equal to the width of the lugs 22, with

which the said latch members coöperate. If 50 preferred, the latch members may be tapered to the desired width; but these and other details of construction may be varied within the scope of the invention.

Having thus described the invention, what 55 is claimed is—

1. In a machine of the class described, a member supported for rotation and having a triangular recess, a rhomboidal tooth mounted in said recess, and means for connecting said 60 tooth with said rotary member.

2. In a machine of the class described, a member mounted for rotation and having earth-engaging teeth, and earth-engaging pins connected with said member and engaging 65 the teeth at their inner ends.

3. In a machine of the class described, a member mounted for rotation, a single row of ground-engaging teeth connected with said member and having shanks forming ground- 70 engaging pins extending from the opposite side of the member, and means for securing said teeth including ground-engaging pins inserted into opposite sides of the rotary member and abutting upon the teeth. 75

4. In a machine of the class described, a toothed member mounted for rotation and having radially-extending earth-engaging pins screw-threaded at their inner ends and squared at their outer ends to form wrench- 80 seats.

5. In a machine of the class described, a member supported for rotation and having sockets, teeth in said sockets having shanks extending through the opposite side of the 85 rotary member and provided with ground-engaging points, and reinforcing-bars connected with said rotary member; one of said reinforcing-bars being provided with slots for the passage of the teeth. 90

In testimony that I claim the foregoing as my own I have hereto affixed my signature in the presence of two witnesses.

ALONZO L. DUNAVAN.
